UNITED STATES PATENT OFFICE.

HENRY J. GRISWOLD, OF MADISON, CONNECTICUT.

KNITTED GOODS AND METHOD OF MANUFACTURING THE SAME.

SPECIFICATION forming part of Letters Patent No. 472,875, dated April 12, 1892.

Application filed July 15, 1891. Serial No. 399,578. (Specimens.)

To all whom it may concern:

Be it known that I, HENRY J. GRISWOLD, a citizen of the United States, residing at Madison, in the county of New Haven, State of Connecticut, have invented certain new and useful Improvements in Knitted Goods and Method of Manufacturing the Same, of which the following is a specification.

My invention relates to the manufacture of ribbed tops, cuffs, skirts, and other circular-knitted fabrics requiring welts; and my invention consists in knitting such articles in continuous lengths, and preferably in semi-detached sections, each section with a welt 15 and capable of ready separation from the adjoining sections, without danger of cutting or otherwise injuring the welt or rendering the fabric liable to fray out, as fully set forth hereinafter, and as illustrated in the accompanying drawings, in which—

Figure 1 shows a continuous circular fabric knit in semi-detached sections adapted to be severed and embodying my invention. Fig. 2 is an enlarged view indicating the character of 25 the union between the semi-detached sections. Figs. 3 to 9 are diagrammatic views illustrating the manufacture of the improved fabric.

In carrying my invention into practice I 30 make use of an ordinary ribbing knitting-machine having a cylinder with needles and a dial with other needles—such, for instance, as the knitting-machine for which Letters Patent of the United States were granted to me 35 March 17, 1891, No. 448,337. The operation of such machine in producing my improved fabric may be readily understood by reference to the diagrammatic views of the accompanying drawings, in which *a* represents one 40 of the cylinder-needles and *b* one of the dial-needles, it being understood that the operation described with the two needles represented are those which take place upon the entire series of needles in the machine.

Assuming that a portion of the circular fabric has been knit and that it is desirable to 45 form a welt and then thereafter continue the knitting of the circular fabric, the operation is as follows: Having knitted a portion of ordinary ribbed fabric *C*, Figs. 1 and 2, I put the ribbing-needles out of action, a loop 2 be-

ing retained upon each ribbing-needle, as shown in Fig. 3. With the cylinder-needles still remaining in action, I knit several rows to make a short section 4 of plain fabric, to 55 prevent the work raveling back. I then break the yarn off or withdraw the yarn-guide, so as to prevent the yarn being fed to the needles during one revolution of the machine, which causes the stitches to be cast off from the cylinder-needles, leaving the portion 4 detached, 60 the work remaining suspended from the ribbing-needles by the series of isolated or separated loops 2, as shown in Figs. 1 and 5. Now to form a fast welt on the following section *c'*, one revolution is given to the machine when the latches of the cylinder-needles will be opened. The ribbing-needles then being put into action and yarn being fed to the needles, by one revolution of the machine loops 70 are placed upon both cylinder and ribbing needles, as shown in Fig. 7, the ribbing-loops 3 being drawn through the previous loops 2. Now the ribbing-needles are again put out of action, the work being suspended from them 75 by the loops 3 as it was before suspended by the loops 2. While the ribbing-needles remain out of action I knit several plain rows to form a section 7 Fig. 8, and I then put the ribbing-needles into action and unite the se- 80 ries of loops 3 with the last row in the portion 7, as shown in Fig. 9, thus forming a fast round welt, after which I proceed to knit the remainder of the section *C'* in ordinary ribbed work. A slack course may be knitted a few 85 courses from the end of each section, as is usual, serving as a guide for running the ribbed top or cuff onto the plain knitting-machine. After the desired number of sections have thus been knit together in one continu- 90 ous fabric, as above described, they may be very readily disconnected by cutting through the loops 2, (the draft on which in knitting stretches them much beyond the length they would otherwise have,) thereby leaving each 95 section of fabric with a welt *w* upon one end and at the other a loose course to facilitate putting onto the needles of the machine for forming the leg of a stocking or other article.

During the last course, before putting the 100 dial-needles out of action previous to commencing the welt, I may introduce a strong

linen or cotton thread, which may be drawn out to sever the articles one from the other instead of severing the loops 2, as described.

If this method of knitting semi-detached sections is used in connection with two and one, three and one, or other than one and one ribbed work, it will be necessary, in order to produce a fast welt, to put every alternate cylinder-needle out of action in making the first two or three courses of the welt.

I claim as my invention—

1. A continuous circular-ribbed knitted fabric consisting of a series of sections, each having a fast welt at one end and each section connected to the adjacent section by a series of isolated loops and having a section of plain fabric 4, substantially as set forth.

2. As a new article of manufacture, a continuous circular-ribbed knitted fabric in sections connected by a series of isolated loops, each extending from one section to a welt of the adjoining section, substantially as set forth.

3. The within-described improvement in the art of knitting circular-ribbed fabrics with welts, the same consisting in knitting a body-section 25 c of ribbed work, then throwing the ribbing-needles out of action, with their loops retained upon them and knitting a section 4 upon the cylinder-needles only, then 30 throwing the stitches off of the cylinder-needles, and then putting the ribbing-needles into action and knitting one course on all the needles, then again throwing the ribbing-needles out of action, with their loops retained 35 upon them and knitting a section upon the cylinder-needles, and then throwing the ribbing-needles again into action and knitting ribbed work, as usual.

In testimony whereof I have signed my name to this specification in the presence of two subscribing witnesses.

HENRY J. GRISWOLD.
